UNITED STATES PATENT OFFICE.

JAMES A. FENTRESS, OF NORFOLK, VIRGINIA.

WINDOW.

1,418,550.

Specification of Letters Patent. Patented June 6, 1922.

Application filed July 23, 1921. Serial No. 487,101.

To all whom it may concern:

Be it known that I, JAMES A. FENTRESS, a citizen of the United States, and resident of Norfolk, in the county of Norfolk and State 5 of Virginia, have invented certain new and useful Improvements in Windows, of which the following is a specification.

My invention relates to improvements in windows of that type in which the sashes are 10 mounted for both sliding and swinging movements whereby they may be manipulated for convenience in cleaning and repairing the same or for other purposes.

More particularly it is a purpose of my invention to provide means whereby opening or closing movement of either sash will impart corresponding movement to the other sash, and in association with such an arrangement to provide other means of a simple and inexpensive nature which will eliminate the necessity of sash cords, pulleys and 20 weights to retain the sashes in desired adjusted positions.

Another purpose of my invention is to 25 provide an arrangement including a screen section in each sash and to so dispose said screen sections relatively that when either sash is moved to an open position, its attached screen section will be brought into 30 position to close a portion of the space previously occupied by the other sash.

A further purpose of my invention is to 35 provide a structure which is capable of accomplishing all of the foregoing and which may be associated with window frames of standard construction without material alterations thereto and with a minimum of time, trouble and expense.

My improved window construction consists essentially of a window frame and a 40 sash frame, the latter being pivoted to the window frame for swinging movement and in turn slidably receiving the sashes. In association with this structural arrangement it 45 is my further purpose to provide weather strips to maintain a tight fit between the window and sash frames when the latter is in its normal closed position with respect to the former.

With the foregoing and other purposes in 50 view, my invention consists in the novel features of construction, combination and arrangement of parts as will be hereinafter more fully described, illustrated in the accompanying drawings and claimed. It is to be understood, however, that the structure

illustrated is merely intended as a disclosure of the essential features of my improvements in a preferred form and that various changes and desirable additions may be made in and 60 to the same within the scope and spirit of my invention as particularly defined in my claims.

In the drawings, wherein like characters of reference denote corresponding parts in 65 the different views:—

Fig. 1 is a front elevation of a window embodying my improvements;

Fig. 2, a vertical transverse section on the line 2—2 of Fig. 1;

Fig. 3, a view similar to Fig. 2 showing the manner in which the sash frame may be 70 swung relative to the window frame, and also showing the respective sashes moved, to open position;

Fig. 4, a transverse section on the line 4—4 of Fig. 1;

Fig. 5, a vertical section on the line 5—5 of Fig. 1; and

Fig. 6, a transverse section on the line 80 6—6 of Fig. 5.

Referring now to the drawings in detail, 10 designates, generally, the main window frame, the same consisting of the usual sill 11, vertical side members 12 and upper 85 transverse connecting member 13. Disposed within this main frame is a sash frame, designated generally at 14 and consisting of a pair of side sections which are of duplicate construction, slidably receiving between 90 them the upper and lower sashes 15 and 16, respectively.

Each side section of the sash frame consists of a pair of inner and outer guide strips 95 17 and 18, respectively, which extend the full length of the frame and are secured together in relative parallel spaced relation by means of metallic connecting pieces 19, which are desirably embedded in the outer faces of the guide strips so that the latter 100 present a smooth unbroken surface, and whereby the space between them is rendered unobstructed to receive the vertical stiles or sides of the sashes.

Any desired number of connecting pieces 105 19 may be provided and arranged as desired, one of them, however, being located intermediate the ends of each side section at a point preferably midway thereof, a central opening being provided in each of the latter 110 pieces to receive a stub shaft 20, one of which projects inward from each of the vertical

side members 12 of the main frame. The sash frame, through the instrumentality of the intermediate metallic connecting pieces 19 and the stub shafts 20, is thus connected 5 to the main frame for swinging movement about a horizontal axis and as is apparent, may be swung from its normal closed position illustrated in Figures 1 and 2 to any desired angular relation with respect to the 10 main frame as intimated by the showing in Fig. 3. By such an arrangement it is clear that the sashes may be readily manipulated for cleaning, repairing or other purposes, since the same are at all times slidable within 15 in the sash frame and in the position of the latter shown in Fig. 3, are removable therefrom as will hereinafter become more fully apparent.

Any desired means may be provided to 20 releasably secure the sash frame in its normal closed position, one preferred means as herein illustrated consisting of a spring latch 21 carried by the sash frame, cooperating with a keeper carried by the main frame. 25 These elements are desirably located at the top of the window structure on the inside and a cord may therefore depend from the latch member whereby the same may be conveniently manipulated to released position. 30 By pulling this cord the latch is released from its keeper and the sash frame may then be swung about its axis of rotation to any desired position, but when it is swung to a closed position it is locked by automatic 35 engagement of the latch with its keeper. In this connection it is to be noted that the lower portion of the sash frame swings outward and the upper portion swings inward. This is necessitated by the slope of the sill 40 11, particularly when my improvements are incorporated in windows of the type at present in common use, the lower ends of the guide strips being beveled to seat against the sill and a stop strip 22 preferably being 45 secured transversely of the main frame at the top thereof to serve as an abutment to limit outward swinging movement of the upper portion of the sash frame beyond a predetermined limit.

50 The inner faces of the vertical stiles or side portions of the respective upper and lower sashes are arranged in abutting relation, as best shown in the sectional views, Figures 4 and 6, while their outer faces are 55 respectively disposed in abutting relation with opposite adjacent faces of the guide strips 17 and 18. Said sashes are thus freely slidable within the sash frame, but are held against all other movements relative thereto. 60 It is thus apparent that pressure exerted against either sash in the direction of the other sash will operate to frictionally bind the latter sash against one or the other of the guide strips 17 or 18 and at the same 65 time frictionally bind the two sashes to-

gether, whereby both of them are rendered incapable of sliding movement. With this condition present I am enabled to utilize a commercial form of device 23 consisting of a cam operated plunger to exert pressure 70 against one of the sashes and thus hold both sashes in any desired slidably adjusted position. This device is preferably secured to one of the inner guide strips 17 as best shown in Fig. 4, in such position that the 75 plunger element thereof operates against the adjacent vertical stile of the inner sash. Only a single device of this kind is needed and it may be secured to any one of the guide strips, but it is apparent that more 80 than a single one may be provided and that in such an event they may be disposed as desired.

It is to be understood that the sashes 85 15 and 16 may be of any desired construction and may be of the usual half-length with respect to the window frame, but in the present instance I desirably form both sashes of three-quarter length or substantially so and also provide means whereby sliding movement of either sash imparts corresponding 90 movement to the other sash.

The lower substantially one-third portion of the upper sash and the upper substantially one-third portion of the lower sash 95 are formed of screen sections 24 and 25, respectively. When both sashes are in their normal closed position the window is fully closed, since the intermediate portion of the upper sash covers the screen section of the lower sash and the intermediate portion of the lower sash covers the screen section of the upper sash. When the lower sash is raised and the upper sash is lowered, however, the screen section of the lower sash is 100 moved into position to close the space opened by the upper sash and the screen section of the upper sash is moved into position to close the space opened by the lower sash. In other words when both sashes are closed 105 reversal of their positions will dispose the screen sections at the top and bottom of the window, respectively, and a free passage or circulation of air therethrough will be permitted, while similarly when both sashes are 110 open reversal of their positions will effect complete closure of the window.

The means whereby sliding movement of either sash imparts corresponding movement in a reverse direction to the other sash 115 consists essentially in the present instance of a rack member secured to each sash and an idler pinion operating therebetween. Desirably duplicate arrangements of this kind are provided at each side of the window 120 to assure smooth and even operation of the sashes, but obviously the desired results will be accomplished if the arrangement is provided at one side of the window only. As best shown in Figures 4 and 6, the adjacent 125

faces of the vertical stiles or side portions of the respective sashes are longitudinally recessed and secured in the recess of the upper sash is a rack 26, while secured in the recess 5 of the lower sash is a rack 27. These racks are arranged in facing relation and are relatively spaced and the pinions 28 which mesh with them are rotatably journaled on the stub shafts 20.

10 Disposed between the racks above and below the pinions 28, are longitudinally channeled strips 29, the channels of which have rubber or felt 30 therein contacting with the inner faces of the side members 12 of the 15 main frame whereby a weather tight fit is produced between said main frame and the sash frame when the latter is closed—see Fig. 6. The channeled strips are secured in position between the racks by suitable fasteners passing through the metallic pieces 19 and as a result form permanent elements of the sash frame side sections.

In association with the structural arrangements recited in the foregoing, means has 25 been provided to eliminate the necessity of sash cords, weights and pulleys to retain the sashes in desired slidably adjusted positions. A lever 31 is pivoted to one of the guide strips, preferably upon one of the securing 30 elements passing through the middle metallic piece 19, and has an end thereof bent to engage between the teeth of the adjacent pinion 28, in which position it is normally held by a spring 32, thereby preventing rotation of the pinion and consequently locking the sashes against sliding movement. A 35 finger engageable portion of this lever projects beyond the outer face of the guide strip to which it is pivoted so that by pressing 40 the same the other end of the lever is moved out of engagement with the pinion and the latter is then free to rotate. After desired adjustment of the sashes has been effected the lever is released and its spring automatically 45 causes its inner end to engage the pinion, and thus lock the sashes against movement.

From the foregoing description taken in connection with the accompanying drawings, 50 it is believed that the construction, operation and advantages of my improvements will be fully understood, and while I have herein disclosed one specific embodiment of my invention it is apparent that various modifications and changes may be made within the 55 scope and spirit of my invention as defined in the appended claims.

I claim:

1. A window including a main frame, a 60 sash frame mounted for swinging movement within said main frame, sashes slidable within said sash frame, and weather strips carried by said sash frame and disposed between adjacent faces of said sashes for

engagement with the main frame to provide a weather-tight fit between said frames. 65

2. In a window, the combination of a main frame, a sash frame mounted for swinging movement within said main frame, sashes slidable within said sash frame, means whereby sliding movement of one sash imparts corresponding movement to the other sash, and weather strips disposed between said sashes and engageable with said main frame. 75

3. In a window, the combination of a main frame, a sash frame mounted for swinging movement within said main frame, upper and lower sashes slidable within said sash frame, means whereby sliding movement of either sash imparts sliding movement to the other sash in a reverse direction, and weather strips carried by the sash frame between said sashes and engageable with the main frame. 80

4. In a window, a main frame, a sash frame mounted for swinging movement within said main frame, said sash frame including inner and outer guide strips, means securing said strips together and holding 90 them in parallel spaced relation, upper and lower sashes slidable between said guide strips, and weather strips carried by said securing means and disposed between said sashes engageable with said main frame. 95

5. In a window, a main frame, a sash frame mounted for swinging movement within said main frame, said sash frame including inner and outer guide strips, means securing said strips together in parallel 100 spaced relation, upper and lower sashes slid- able between said guide strips, the adjacent faces of the side stiles of said sashes being channeled, a rack secured in the channel of each stile, a pinion carried by the main frame and meshing with the respective racks, and weather strips carried by said securing means and disposed between the 105 respective sashes and adjacent racks thereof, said weather strips being engageable with 110 the main frame.

6. In a window, a main frame, a sash frame mounted for swinging movement within said main frame, said sash frame including inner and outer guide strips, means 115 securing said strips together in parallel spaced relation, upper and lower sashes slid- able between said guide strips, the adjacent faces of the side stiles of said sashes being channeled, a rack secured in the channel of each sash, a pinion carried by the main frame and meshing with the respective racks, and a member pivoted to said securing means 120 and cooperating with said pinion to lock said sashes in different adjusted positions. 125

In testimony whereof I hereunto affix my signature.

JAMES A. FENTRESS
